To all whom it may concern:

Be it Known that I, N. S. Fig: 1, is a foot;

Fig: 2, the bottom plate;

Fig: 3, an end plate;

Fig: 4, the front plate of the oven with its door.

Fig. 5. the hearth which fits on the front, 2 (see Fig. 11)
of the ash-box;

Fig. 6. the front plate of the fire-box, with its doors;

Fig. 7. the "pot-hole" top-plate, and

Fig. 8. the open-work removable top.

The foot is ornamented with the center-piece, a, surrounded by scroll work, b, and with the side scrolls, c, c, as shown; and is of the shape represented in Fig. 1. - The hearth plate is of the shape shown by Fig. 2 and is ornamented with a shell, d, & a crimped scroll, e, in each corner, and the figured border mouldings, f, f, f, f, as exhibited. Each end-plate is of the shape shown by Fig. 3 and bears the composition of scrolls, g; leaves, h; flowers, i; and fruits, j; surrounded by the figured moulding, k, as shown. A vase of flowers, l, ornaments each side of the front-plate of the oven; and the rectangular oven door is ornamented by the center-piece, o, crimped edging, m, and broad spreading scroll-leaves, n, as represented in Fig. 4. - The hearth of the ash-box is of the shape shown by Fig. 5, and is ornamented by the figured border moulding, p, having scroll-like ends, as shown. - The front-plate of the fire-box has the compound ornament, q, at each end, and the rectangular fire doors are together ornamented by the one large compound center-piece A, as shown in Fig. 6. The "pot-hole" top plate is of the form, and is ornamented by the figured border moulding, r, shown in Fig. 7. The removable top consists of the ornamental open-work scroll leaf composition represented by Fig. 8.

What I claim as my invention or production and desire to secure by Letters Patent, is, the configuration, and arrangement of ornamental figures, forms and mouldings, herein described & Exd shown in the annexed drawings, the whole constituting a design for a S. M. parlor cooking Stove.
